SOCKET WRENCH

Frank U. Winchester, Lansing, Mich., assignor to
 Motor Wheel Corporation, Lansing, Mich., a corporation of Michigan

Application March 2, 1932, Serial No. 596,219

2 Claims. (Cl. 287—119)

This invention relates to socket wrenches and more particularly to wrenches of that type suitable for use in securing and removing the hold or clamp nuts on heavy duty vehicle wheels.

5 The invention has for its principal objects the provision of a socket wrench which is of simple and inexpensive construction, which may be utilized for securing and removing the clamp nuts of vehicle wheels where the periphery of the 10 wheel overhangs the clamp nut, which is designed to withstand the extreme pressures required to secure and remove such clamp nuts, and which is adapted to be folded into compact arrangement for storage. Other more or less incidental 15 and ancillary objects will appear from the following description of the invention.

Socket wrenches adapted for use in removing and installing vehicle wheels on heavy duty trucks and trailers must be strong enough to withstand 20 the very great pressure required in securing and removing the clamp nuts for such wheels. Inasmuch as the shape of vehicle wheels of this character as regards the overhang of the periphery and tire carrying part of the wheel in relation 25 to the portion of the wheel carrying the clamping nuts varies greatly, it is necessary to provide a socket wrench which can be conveniently rotated without interference from the overhanging portion of the wheel when placing and removing 30 the clamping nuts. For this reason the socket wrenches in use heretofore have been of relatively complex and expensive construction.

This invention provides a socket wrench which by reason of a pivotal handle connection may be 35 rotated continuously in securing a clamping nut without interference from any part of the wheel or vehicle and without striking the ground. This greatly facilitates the ease and speed with which clamp nuts may be installed and removed. Accordingly the socket wrench embodying this invention is suitable for use with substantially all types of vehicle wheels regardless of the overhanging relation of the tire carrying portion to the body of the wheel, and is at the same time 40 of very simple and inexpensive construction. This is accomplished by forming the socket wrench in two parts, one part comprising the socket member itself and being formed of cast metal, and the other part comprising a steel bar handle 45 removably and pivotably secured to the socket member in a manner whereby the latter may be rotated with the handle at an angle thereto. In this manner a socket wrench is produced, none 50 of the parts of which require machine work, with

one exception, which will be referred to herein-after.

An example of a socket wrench embodying the invention is illustrated in the accompanying drawing, in which:

Figure I is a side view in elevation of the socket wrench, a portion thereof being shown in section to illustrate the manner in which the handle is secured to the socket member.

Figure II is a side view in elevation of the 10 handle shown in Figure I.

Figure III is a cross sectional view taken on the line III—III of Figure I.

Figure IV is an end view in elevation of the structure shown in Figure I.

The wrench embodying this invention comprises a substantially tubular socket member 10 formed of cast metal and preferably a steel bar handle 11 removably and pivotably connected thereto. The wall of the socket member 10 adjacent one extremity thereof is cast to form a plurality of flat surfaces 12 adapted to engage similar flat surfaces of a hold or clamping nut utilized for the purpose of securing a vehicle wheel to a hub flange. A substantially rectangular opening 13 is provided in the opposite extremity of the socket member 10 for a purpose to be described presently. Openings 14 for the reception of one extremity of the handle 11 are formed in the enlarged portion of the wall of the socket member 10 adjacent the opening 13 and extending in a direction at right angles thereto.

The handle 11 has an end portion 15 bent at right angles to the remainder thereof. The portion 15 is provided adjacent the extremity thereof with an annular groove 16, the formation of which constitutes the only machine work required in the construction of the socket wrench embodying this invention. The annular groove 16 is located about the end portion 15 at a suitable distance from the extremity thereof to bring the groove in alignment with the opening 13 when the end portion 15 of the handle 11 is inserted into the openings 14 in the socket member 10.

The handle 11 is removably secured to the socket member 10 by means of a resilient annular metal clip 17 which is adapted to be inserted through the opening 13 in the end of the socket member 10 whereby it may be snapped into position in the groove 16 formed in the handle 11 after the end portion 15 thereof has been positioned within the openings 14.

The metal clip 17 which is best shown in Fig-

5

ure III is of substantially annular formation with the opposite extremities 18 bent out of alignment and with its mid-portion 19 extended to provide means for securely locking the handle 11 to the socket member 10 when the clip 17 is in position within the groove 16. As has been stated the clip 17 may be inserted through the opening 13 in the end of the socket member 10. Likewise it may be removed through the same opening by springing the extremities 18 thereof apart so that it is freed from the end portion 15 of the handle 11. In this manner a new socket member may be readily affixed to an old handle or a new handle affixed to an old socket member in case either of these parts should become broken.

From the foregoing description it will be apparent that the handle 11 when operatively connected to the socket member 10 may be rotated about the socket member 10 on the vertical axis formed by the end portion 15. While normally the body portion of the handle 11 is rotated to a position in which it lies at right angles to the longitudinal axis of the socket member 10 for operating the socket member, it will be apparent that the socket member may also be operated by means of pressure applied to the handle 11 when the handle is in any position other than parallel to the longitudinal axis of the socket member. The handle may be rotated to a position in which the body portion thereof overlies the socket

member 10 whereby the entire socket wrench is made more compact for storage.

While a specific embodiment of the invention has been shown and described for the purpose of illustration it should be understood that the invention is not limited thereto but is coextensive with the scope of the appended claims.

I claim:

1. A coupling comprising a socket member having an opening therein for the reception of a handle member, a handle member having an end portion positioned within said opening, an annular groove formed in the end portion of said handle member for the reception of a semi-circular band, a semi-circular band positioned within said groove with its ends turned outwardly to contact the socket member, and a recess in the socket member through which said band may be inserted and withdrawn. 15

2. A coupling comprising a socket member having an opening therein for the reception of a handle member, a handle member having an end portion positioned within said opening, an annular groove formed in the end portion of said handle for the reception of a semi-circular band, a semi-circular band positioned within said groove with its ends and an intermediate portion turned upwardly to contact the socket member, and a recess in the socket member through which said band may be inserted and withdrawn. 25 30

FRANK U. WINCHESTER.
